UNITED STATES PATENT OFFICE.

ALLAN COWPERTHWAIT, OF BROOKLYN, NEW YORK, ASSIGNOR TO WALTER L. TYLER, OF BROOKLYN, NEW YORK, AND ALONZO B. SEE, OF NEW YORK, N. Y.

SAFETY-STOP FOR ELEVATORS.

SPECIFICATION forming part of Letters Patent No. 703,548, dated July 1, 1902.

Application filed April 15, 1902. Serial No. 102,952. (No model.)

To all whom it may concern:

Be it known that I, ALLAN COWPERTHWAIT, a citizen of the United States, residing at the city of New York, in the borough of Brooklyn and State of New York, have invented certain new and useful Improvements in Safety-Stops for Elevators, of which the following is a full, clear, and exact description.

This invention relates to safety appliances for elevators, the object being to provide a simple and effective apparatus which will automatically stop the car without serious shock when the speed in lowering exceeds a certain predetermined maximum.

15 The present invention is a modification of the device shown in United States Patent No. 637,396, issued to Nils O. Lindstrom November 21, 1899. The said patented construction involves a pair of jaws on each side of the car, which are thrown together to clamp the guide-rails by putting tension upon a rope which passes around a pair of movable pulleys. The strain of the rope draws the pulleys together, and they in turn carry wedges 20 between the free ends of the jaws to cause them to clamp the guides. The tension on the rope is created automatically by a gripping device, which is thrown into action by a centrifugal governor. The rope is normally secured at one end to the upper end of the shaft and passes around the governor carried by the car. When the gripping device, which is also carried by the car, is thrown into action, it necessarily puts a tension on 25 the rope, which tension is utilized in the manner before described. In the present case the rope instead of running up and down through the shaft is carried by the car, and when the speed of the car becomes excessive 30 one end of the rope is automatically caught and held by a retaining device permanently fixed to the shaft, the other end of the rope remaining fixed to the elevator. When this action takes place, the continued movement 35 of the car puts the necessary tension on the rope and the movable pulleys act upon the wedges and clamp the jaws to grip the guide-rails.

The details of the invention will be described with reference to the accompanying drawings, in which—

Figure 1 is a vertical section of an elevator shaft and car, showing parts of the mechanism in elevation. Fig. 2 is a plan of the mechanism on top of the car. Fig. 3 is a plan of the bottom of the car, and Fig. 4 is a detail of the end of the rope.

The side walls of the shaft are indicated by A, to which are fixed the usual vertical guide-rails a. There is also fixed to each side wall a vertical cam-track b, arranged at one side of the guide-rails and having at regular intervals depressed portions b' for a purpose which will hereinafter appear, the depressed portions on one side of the shaft alternating in position with those on the other side. There are also fixed to the side wall of the shaft in a vertical row a number of brackets c, from which project two hooks c', each bracket being located a little above one of the depressions b' of the cam-track, there being one bracket for each depression.

The elevator-car is indicated by B. Preferably on top of the car and adjacent to each side is mounted in suitable bearings e' a shaft 75 e, upon one end of which there is a crank f', carrying a trolley-wheel f, adapted to run upon the rail b, to which it is adjacent. At the other end of each shaft is a bell-crank lever, one arm of which, g, is upwardly inclined 80 toward the opposite wall of the shaft and carries a weight g', adjustable in position thereon, and the other arm, g², being fork-shaped and provided at its outer end with two U-shaped seats g³, opening upward at a position 85 closely adjacent to the side of the shaft, but so related to the other parts that when the trolley f is against the straight portion of the cam-track or in that plane the seats g³ will be in a vertical line above the hooks c'; but when 90 the trolley is in one of the depressions b' of the cam-track the said seats g³ are nearer the middle of the shaft and out of line with the hooks c'. To the bottom of the car and on each side are fixed a pair of guide-sheaves i 95 and i', and along the middle of the bottom of

the car are mounted in a suitable frame, two sets of pulleys or blocks *k* and *k'*, so mounted in the frame as to be capable of sliding toward and away from each other in the manner fully described in the patent before mentioned. These pulleys are normally separated by the spring *s* between them. Each block is attached to a wedge *w*, adapted to be moved between the free ends of a pair of jaws *o*, pivoted at *o'* and having clamping-faces *o''*, embracing the guide-rails *a*. It will be seen that when the blocks are drawn toward each other each pair of jaws will be closed upon the respective rails and create a friction, which is utilized herein to stop the car.

r is a rope each end of which carries a cross-bar *r'*. (See Fig. 4.) The cross-bar at one end of the rope normally rests in the seats *g³* on one of the bell-crank levers on top of the car. The rope leads thence downward between the side of the car and the shaft over the sheaves *i*, thence in a loop around the sheaves in the blocks *k* and *k'* as many times as there are sheaves in said blocks, thence around the sheave *i'*, thence up the shaft on the opposite side of the car to the second bell-crank at the top, where its cross-bar *r'* is seated in the seats *g³*.

As the car travels up and down the shaft at normal speed or less the trolley-wheels on each side ride along their respective cam-tracks and into and out of the depressions *b'* as each one is passed. The wheel is caused to enter the depressions by the weight *g'*, the effectiveness of which can be determined by setting the weight at the proper distance from the axis upon which it turns. When the car is traveling downward, the trolley enters a depression just before the seats *g³* reach the level of the hooks or seats *c'*, and the seats are then moved outward, carrying the cross-bar *r'* on the end of the rope clear of the hooks and allowing the car to pass without the rope being caught. When the downward speed of the car exceeds the predetermined maximum, either by accident or design, the trolley will pass a depression so rapidly that the weight is not given time to force it into the depression. The consequence is that the cross-arm on the rope is not removed out of range of the hooks *c'* and is caught thereon, the seats *g³* passing on, relieved of the end of the rope. It will now be seen that one end of the rope is fast to the wall of the shaft, while the other end is fast to the car, it being seated in the other bell-crank. Hence the further movement of the car will put a tension upon the rope and draw the blocks *k* and *k'* together at a speed determined by the number of sheaves in the blocks. This will cause the wedges *w* to act upon the clamping-jaws and clamp the guide-rails *a*, creating a gradually-increasing friction therewith, which eventually stops the car. The graduation of the stop can be predetermined to any extent by

the number of sheaves in the blocks and the nature of the frictional surfaces.

Either end of the rope may be shifted from its seat on the elevator to a seat on the shaft, depending upon which of the bell-cranks acts first. As soon as the cord has been caught on a seat in the shaft the tension at once throws the seat on the opposite bell-crank outward until it is stopped by the crank *f'* striking a lug *p* on the bearing *e'*. This prevents the apparatus from being thrown out of order by tilting the bell-crank too far and retains the parts in condition to immediately become operative when the car is again started.

Having described my invention, I claim—

1. A safety device for elevators, consisting of a cord carried by the car, means for automatically engaging said cord with the shaft when the speed of the car becomes abnormally great, stopping devices for the car and means whereby the tension thus created on the cord by the moving car will operate the stopping devices for the car, substantially as described.

2. A safety appliance for elevators, consisting of a cord carried by the car, devices fixed in the shaft for engaging with the cord, automatic means for causing said engagement when the speed of the car becomes excessive, a gripping device actuated by the cord when it is thus engaged, said gripping device adapted to act upon the guide-rails of the car, for the purpose of stopping the car.

3. In a safety device for elevators, the combination of a pair of clamps adapted to engage with the guide-rails of the car, a pair of movable blocks adapted to actuate said clamps, a cord looped around said blocks and carried by the car, and means for attaching said cord to the side of the elevator-shaft when the speed of the car becomes abnormally high, substantially as described.

4. In a safety device for elevators, the combination of a pair of clamps adapted to engage with the guide-rails of the car, a pair of movable blocks adapted to actuate said clamps, a cord looped around said blocks and carried by the car, said cord being normally fixed at each end to the car and means whereby one end of the rope will be detached from the car and fixed to the side of the elevator-shaft when the speed of the car becomes abnormally high.

5. In a safety device for elevators, the combination of a car, a cord carried thereby and having its ends normally fixed thereto, stopping devices for the car operated by said cord when put under tension, stationary hooks fixed at intervals in the elevator-shaft, means carried at the extremities of the cord for engaging with said hooks and means whereby the overspeeding of the car will cause said engagement, substantially as described.

6. The combination of an elevator car and shaft, stopping devices for the car, a rope car-

ried by the car and adapted when under tension to operate said stopping devices, a seat on the car for the end of the rope, a series of stationary seats fixed in the shaft and means for shifting the end of the rope from its seat on the car to one of the seats in the shaft, for the purpose set forth.

In witness whereof I subscribe my signature in presence of two witnesses.
